UNITED STATES PATENT OFFICE

2,229,972

SHAVING DEVICE

Neil Holsclaw, Chicago, Ill., assignor, by mesne assignments, to American Safety Razor Corporation, Brooklyn, N. Y., a corporation of Virginia

Application May 7, 1937, Serial No. 141,259

4 Claims. (Cl. 30—43)

This invention relates to razors of the rotary type; and the main objects of the invention are to provide for a more positive and effective interfitting and cutting adjustment of the shear members; to provide for continuous automatic adjustment of the cutting and shear members; to provide such means adapted to compensate for wear; to provide for ready assemblage and renewal of parts; to provide a razor of this kind of simple design and few parts and adapted for ready manufacture and maintenance at small cost; and to provide such a razor adapted for dry operation and without lather.

This invention is illustrated by the accompanying drawing in which:

Figure 1 is a perspective view of a preferred embodiment of my razor, showing its cutting side.

Fig. 2 is an enlarged face view of the cutting head of the razor.

Fig. 3 is mainly a longitudinal axial section on the line 3—3 of Fig. 1 through the razor head with the rotor and driving gear in elevation.

Fig. 4 is a cross-section through the head on the line 4—4 of Fig. 3, the cutting shear feature being at the right and the exit for beard cuttings being at the left.

Fig. 5 is a section through the right end of the head of Fig. 3 on the line 5—5.

Fig. 6 is an enlarged section through the left end of the head of Fig. 3 on the line 6—6.

Fig. 7 is a perspective view of one of the two end journal bearing blocks for the rotor, such as shown in position on Fig. 6.

Fig. 8 is a fragmentary section on the line 8—8 of Fig. 3 and shows mainly how the head gear shaft shown in Fig. 3 is held in place.

Fig. 9 is a rear elevation of the razor head and cutter plate as viewed from the left of Fig. 4.

Referring more in detail to these views, the razor as a whole comprises a combination handle and motor housing 1 on one end of which is a removable housing head 2 containing a shear rotor 3.

A two-conductor electric power cord 4 is connected to the opposite end of housing 1, as shown in Fig. 1. A manual device 5 controls starting of the motor as will be understood through the latter, mounted in chamber 6 and connected to shaft 7, is not actually shown. But for present purposes this shaft 7, jointed at 7', may be regarded as the motorizing power source.

The generally cylindriform hollow frame or head 2 is laterally apertured longitudinally as at 8 on Figs. 2 and 4. On one edge of this narrow slot or beard receiving aperture 8 is a fixed blade

or cutter 9. Along the opposite edge is a series of tapered guard fingers 10 pointing toward said blade and positioned to hold the skin of the person being shaved from bearing against the cutting edge of the blade, but permitting the beard to be 5 so engaged.

In use said blade is mechanically integral with the head casting, but actually the blade member 9 is removably hinged at 11 and secured by screws at 12 for ready access to chamber 13 and for blade 10 renewal when necessitated by cutting edge wear. This member 9 is cylindroarcuate and occupies about 180 degrees on the head 2, as shown by Figs. 4 and 5.

The rotor 3 is journaled at its ends on the end walls 2' of head 2, as at 16—16 on Figs. 3 to 6. The bearing pivots 17 of the rotor fit somewhat loosely in the wall cups 16, but the rotor is resiliently held snugly against the cutter side of head 2 by the spring and block mechanism shown by 20 Fig. 6 and now to be described. Here the bearing walls 2' have slots 21 and 22 extending outward from the cups 16 at about 90 degrees from each other. Each slot 21 lies about midway of the cutting and hinge edges of blade 9 and when the 25 blade is swung open access may be had to rotor 3 for its removal or replacement by sliding of the rotor pivots 17 in head slots 21.

Each slot 22 extends outwardly part way toward a corresponding hinge pivot 11, about 90 degrees 30 from the plane of slots 21, but terminates in a seat 25 containing a screw 26 which extends outwardly in a threaded hole 27 for adjusting the inward thrust of the corresponding bearing block 29 against the rotor pivot 17. In order to assure 35 uniform and constant pressure of the spiral shear ribs 31 of rotor 3 against the cutting edge of blade 9, I interpose an inwardly concave leaf spring 33 between the screw 26 and block 29, the latter being notched at 34—34 on its outward corners 40 to receive the ends of spring 33, as in Figs. 6 and 7, and the middle part of spring 33 being seated against the inner end of screw 26. Block 29 remains mainly in its guide slot 22.

The ribs 31 are rectangular in cross section and 45 the leading square-cornered shear edge 31' forces the hairs against the edge of blade 9.

The rotor 3 is operatively connected to the power supply shaft 7 by means of the coaxing bevel gears 41 and 42 fixed on shafts 7 and 43 50 respectively, and spur gears 44 fixed on the ends of shaft 43 where they coact with the toothed gear ends 45 of the rotor 3. The shaft 43 is held in place by a journal block cover strip 47 secured by screws 48. The rotation of shear 55

member 3, indicated by arrow 48, is counter-clockwise as viewed in Fig. 4 and is at a rather high speed.

In order to enable continuous operation of the razor without clogging or any special attention the semicylindrical blade member 9 is provided with a series of openings 50, as shown on Fig. 9, for the escape of beard cuttings.

In use the razor is connected to a room lighting circuit and the motor set going by means 5. Then the user grasps the handle part 1 and draws the cutter face of head 2 (upper right-hand part on Fig. 4) over the surface to be shaved, preferably "against the grain."

It is to be understood that some of the details set forth may be altered or omitted without departing from the spirit of the invention as defined by the following claims.

I claim:

1. A razor head cylindrically apertured with a spiral shear rotor therein, said head having end walls each provided with a pair of radial slots, one to loosely receive an axial end bearing of said rotor and the other to house an adjustable inward spring thrust member which is provided to bear against the proximate rotor bearing and to assure constant shear contactual pressure relation between the rotor and a blade which is carried by said head on its side opposite from the thrust members.

2. In a razor device of the class described, a spirally ribbed shear rotor having a bearing pivot, in combination with a housing including a head having a slot to loosely receive said pivot and also an intersecting slot having therein a spring-supported arcuate faced thrust block to laterally embrace said pivot and retain it in place in the first said slot and to hold said rotor resiliently in its effective shaving position.

3. A motorized razor comprising a hollow head having a rigidly mounted arcuately shaped cut-

ter blade in combination with a resiliently mounted rotor having mutually spaced spiral arcuately shaped shear ribs to engage said cutter blade, the inner face of the cutter blade being concentric with the outer face surface of said ribs and of like radius, said head having end walls each provided with a pair of radial slots, one to loosely receive an axial end bearing of said rotor and the other to house an adjustable inward spring thrust member which is provided to bear against the proximate rotor bearing and to assure constant shear contactual pressure relation between the rotor and a blade which is carried by said head on its side opposite from the thrust members.

4. In a dry shaver, a casing, a bore in said casing, said casing having end walls, a longitudinal slot in said casing provided with a shearing edge, a rotary cutter of a diameter slightly less than that of the bore mounted for rotation within said bore, a trunnion on each end of said cutter, a diametrical groove in each end wall of the casing directed toward the said shearing edge, a bearing pivot adapted to bear against one side of each trunnion so as to press it toward said shearing edge, said bearing pivot being mounted for sliding movement within said groove, and means for urging said pivots toward said shearing edge, whereby said cutter will be urged against the wall portions of the bore adjacent to said shearing edge, and a groove transversely intersecting said first groove and opening outward and adapted to slidably receive said trunnions, whereby the cutter may be inserted into or removed from its seat within said casing, and a side portion of said casing being removable to permit the cutter to pass through the opening formed by removing said side portion.

NEIL HOLSCLAU. 30
